Filed Mar. 4, 1963, Ser. No. 73,809

Term of patent 14 years

(Cl. D80—11)

FIG. 4

FIG. 1 is a front perspective view taken from one end of a refrigerated display case embodying our new design, the rear of the case being flat and substantially plain, as indicated in FIGS. 2 and 4.

FIG. 2 is an elevational view taken from the end shown in FIG. 1.

FIG. 3 is an enlarged fragmentary cross sectional view taken on line 3—3 of FIG. 1.

FIG. 4 is a top plan view of a refrigerated display case embodying our new design.

The dominant features of our design reside in the portions shown in full lines.

We claim:

The ornamental design for a refrigerated display case, substantially as shown and described.
